UNITED STATES PATENT OFFICE

GEORGE W. CLARK, OF WESTFIELD, MASSACHUSETTS, ASSIGNOR TO EDWARD H. BROADWELL, RECEIVER OF THE WESTFIELD MANUFACTURING COMPANY, OF WESTFIELD, MASSACHUSETTS, A CORPORATION OF MASSACHUSETTS

DESIGN FOR A BICYCLE FRAME OR THE LIKE

Application filed November 15, 1932. Serial No. 45,988. Term of patent 14 years.

To all whom it may concern:

Be it known that I, GEORGE W. CLARK, a citizen of the United States, residing at Westfield, in the county of Hampden and State of Massachusetts, have invented a new, original, and ornamental Design for a Bicycle Frame or the like, of which the following is a specification, reference being had to the accompanying drawing, forming a part thereof.

In the drawing,

Fig. 1 is a plan view of the frame;

Fig. 2 is a side view of the frame;

Fig. 3 is a detail view looking in the direction of the arrows from line 3—3 of Fig. 2, with parts broken away; and

Fig. 4 is another detail view looking in the

direction of the arrows from line 4—4 of Fig. 2, with parts broken away.

The characteristic feature of the design is in the double bars at the top of the frame sweeping from single bar at the head of the frame from which such double bars are streamlined in a diverging manner so as to merge into the lines for the rear fork portions of the frame formed as continuations of the double top bar, leaving the head of the frame as a single post and giving the sense of a double springing arch from the rear wheel hub gradually merging into the single head member without a break in either arch.

The ornamental design for a bicycle frame or the like as shown and described.

GEORGE W. CLARK.
